UNITED STATES PATENT OFFICE.

JONATHAN WRIGHT AND WILLIAM H. MARSHALL, OF PLEASANTVILLE, NEW YORK.
APPARATUS FOR GENERATING AND DIFFUSING WATER-VAPOR INTO THE ATMOSPHERE OF ROOMS.

1,320,724.

Specification of Letters Patent.

Patented Nov. 4, 1919.

Application filed April 29, 1919. Serial No. 293,569.

To all whom it may concern:

Be it known that we, JONATHAN WRIGHT and WILLIAM H. MARSHALL, citizens of the United States, residing at Pleasantville, county of Westchester, State of New York, have invented a certain new and useful Improvement in Apparatus for Generating and Diffusing Water-Vapor into the Atmosphere of Rooms, of which the following is a full, clear, and exact description.

Our invention relates to apparatus for generating and diffusing water vapor into the atmosphere of rooms and has for its object to produce an apparatus by which water will be continuously and uniformly vaporized under given conditions and thoroughly diffused in the atmosphere. It further has for its object to provide means for controlling the amount of vapor produced under given conditions and to provide means for simultaneously controlling the amount of water vaporized during a given time at a plurality of points, one of the means of doing this being the simultaneous regulation of the extent of the superficial area of the water exposed for evaporation. It further has for its object to provide means whereby the extent of surface of the water being vaporized at one of several points can be independently varied.

The following is a description of an embodiment of our invention, reference being had to the accompanying drawings, in which,

Fig. 1 shows a system embodying our invention and comprising two heaters and two vaporizers;

Fig. 2 is a plan view of one of the vaporizers with the heater removed;

Fig. 3 is a side elevation partly broken away showing the lower portion of a heater and the vaporizer located beneath the same; and

Fig. 4 is a section on the line 4—4, Fig. 3.

Referring more particularly to the drawings, 1—1' are radiators which may be either hot water or steam radiators provided with proper means of supplying the heating medium thereto. Below these radiators are castings 2—2', each of said castings having in its upper portion an open compartment or container 3 for water to be vaporized and in its lower portion a closed chamber 4 for the heating medium supplied to the radiator. The bottom of the container 3 has

a slanting floor 5 which separates the water in the water container from the chamber 4, constituting a passage for the heating medium. The water container, as shown, is provided with two barriers 6 extending in the direction of the slant of the floor which divide it into three sections, as shown in Fig. 2. These sections are interconnected with one another by piping 7, provided with cocks 8 whereby one or both of the other sections can be cut off from the left-hand section as may be desired, so as to vary the extent of surface of the water in the container connected with the water supply. By this means the surface of the water in one container can be varied independently of the water in other containers. 9 is the water supply, the same comprising a tank having an inlet provided with an ordinary ball cock 10 for keeping the water therein at a given level and with an overflow pipe 11. This water supply is connected by piping 12 with the two containers 3 in the castings 2—2' through cocks 13 by which one or both of the containers 3 can be entirely cut off. Leading to one end of each chamber 4 of the vaporizer is a pipe 14 and leading from each other end is a pipe 15. The pipes 15 are connected to the respective radiators 1—1', each chamber 4, together with its pipes 14 and 15, constituting the means for supplying the heating medium to the radiator. The pipes 14 are provided with the ordinary valves 16 for controlling the supply of such heating medium.

In operation one or more of the compartments in the container 3 are filled with water, the valves 13 and 8 being set for that purpose. The height of this water is determined by the height of the water in the tank 9, which can be adjusted by means of the ball cock 10. On account of the slanting floor of the water container, the surface of the water in the water container increases with the depth of the water therein and since under given atmospheric and heat conditions water vaporizes at a rate varying with its surface, a variation in the amount of water vaporized can be easily obtained. The level of the water, and as a consequence its exposed surface, is fixed in a general way by the adjustment of the ball cock 10, and its surface in any container is thereafter varied independently of the other containers as desired by cutting off or adding

one or more of the divisions of the water container by manipulation of the cocks 8-8. If desired, a pet cock 18 may be provided in connection with the right-hand division of the water container for the purpose of draining off the water in that division or one or all of the other divisions as may be desired so as to effect a speedy change in the vaporizing surface. 19 is a removable plate to allow access to the water container when desired.

The upper edge of the container from which the plate 19 rises is above the tops of the barriers 6-6, so that if desired the ball cock can be adjusted so as to keep the tops of the barriers flooded and increase the extent of surface exposed for evaporation.

The slanting floor of the container and its division into compartments allow for the common regulation of several vaporizers and the separate regulation of each vaporizer, providing simple means for varying the heated surfaces covered by the water and also the surface of the water exposed to the air and from which evaporation takes place, the evaporation varying with the surface of the water, other conditions being the same.

The water vapor rising from the container passes upward against and around the sections or coils of the radiator, and is there superheated and expanded, the temperature of the radiator being higher than the temperature of the water vapor. The rising current of warm air from the radiator will diffuse the superheated and expanded water vapor out into the room laterally of the radiator (assuming the latter to be adjacent to a wall) so that the water vapor before it is expanded or diffused does not impinge against any chilling surface or mingle with air colder than it is.

By the means described the humidity of the air in a heated room may be kept at any desired point.

In using our apparatus, the containers are filled with water to the desired extent, the level being determined by the adjustment of the ball cock 10. The extent of water surface for any one container is independently adjusted by connecting or disconnecting one or more of the compartments formed by the barriers 6. Thereafter the action is automatic, water being supplied from the tank 9 as fast as it is evaporated in the containers 3. The vapor generated rises and strikes the radiators and is heated by them so as to be expanded and diffused in the atmosphere of the room. By this means a proper degree of moisture can be maintained in a room so as to prevent the injurious absorption by the air of the moisture of objects or persons in the room.

Aside from saving the damage which is prevented by having the air properly mois-

tened, the moisture introduced into the air by our apparatus results in a saving in coal, inasmuch as rooms so moistened do not have to be heated so highly in order to be comfortable as they would be if the air were dry.

The advantages of generating and diffusing water vapor by the method carried out by the apparatus above described are more fully set forth in our Patent No. 1,285,879, dated November 26, 1918.

As will be evident to those skilled in the art, our invention permits of various modifications without departing from the spirit thereof or the scope of the appended claims.

What we claim is:

1. In a vapor generating and diffusing apparatus comprising a radiator, the combination of a passage for a heating medium supplied to said radiator and an open container for water, both located below said radiator, said container having an open top discharging vapor so as to impinge upon said radiator, said water container being adjacent to said passage so as to be heated thereby, means for maintaining a substantially uniform body of water in said container and connections for conveying said heating medium to said radiator through said passage.

2. In a vapor generating and diffusing apparatus comprising a radiator, the combination of a passage for a heating medium supplied to said radiator, and a container for water having an open top to discharge vapor so as to impinge upon said radiator, said water container being adjacent to said passage so as to be heated thereby, means for maintaining a substantially uniform body of water in said container and connections for conveying said heating medium to said passage and to said radiator, said water container having a slanting bottom and means for regulating the height of the water in said container.

3. In a vapor generating and diffusing apparatus comprising a radiator, the combination of a passage for a heating medium supplied to said radiator, and a container for water, said water container being adjacent to said passage so as to be heated thereby, means for maintaining a supply of water in said container, connections for conveying said heating medium to said passage and to said radiator, said water container being divided into compartments, and means for connecting and disconnecting said compartments from the source of water supply so as to vary the extent of water surface in said container.

4. In a vapor generating and diffusing apparatus comprising a radiator, the combination of a passage for a heating medium supplied to said radiator, and a container for water, said water container being adjacent to said passage so as to be heated thereby, means for maintaining a substantially uni-

form body of water in said container, connections for conveying said heating medium to said passage and to said radiator, said water container having a slanting bottom 5 and being divided into compartments, and means for connecting and disconnecting said compartments from the source of water supply so as to vary the extent of water surface in said container.

10 5. In a vapor generating and diffusing apparatus comprising a radiator, the combination of a chamber for a heating medium supplied to said radiator and an open container for water, both located below said radiator, 15 said water container being adjacent to said chamber so as to be heated thereby, means for maintaining a supply of water in said container, connections for conveying said heating medium to said chamber and said radiator, said water container having a slanting bottom, said means for maintaining a supply 20 of water consisting of an auxiliary tank

and means for maintaining the water in said tank at the predetermined level desired in said container for securing the requisite 25 water surface for evaporation and means for regulating the height of the water in said tank.

6. In an apparatus for producing and diffusing water vapor comprising a radiator, 30 an open-top water container located below said radiator, a chamber for a heating medium located below said water container, the floor of said container sloping gradually and being integral with the roof of said 35 chamber, connections leading to said chamber for conveying said heating medium thereto, connections between said chamber and said radiator and connections for supplying water to said container, and means 40 for regulating the height of the water in said container.

JONATHAN WRIGHT.
WILLIAM H. MARSHALL.
